(57) CLAIM

The ornamental design for jewelry article including a hand, as shown and described.

DESCRIPTION

FIG. 1 is a front view of a jewelry article including a hand of the claimed design;

FIG. 2 is a left side view of the design of FIG. 1;

FIG. 3 is a right side view of the design of FIG. 1;

FIG. 4 is a top end view of the design of FIG. 1;

FIG. 5 is a rear view of the design of FIG. 1; and,

FIG. 6 is a bottom end view of the design of FIG. 1.

The broken lines shown in the drawings represent unclaimed portions of the jewelry article including a hand and form no part of the claimed design.

1 Claim, 2 Drawing Sheets
